UNITED STATES PATENT OFFICE.

JOHN P. HENDERSON, OF FRANKLIN, LOUISIANA.

IMPROVEMENT IN ARRANGEMENT OF SUGAR-KETTLE TRAINS.

Specification forming part of Letters Patent No. **29,076**, dated July 10, 1830.

To all whom it may concern:

Be it known that I, JOHN P. HENDERSON, of Franklin, in the parish of St. Mary's and State of Louisiana, have invented a new and useful Improvement in Kettle-Trains for Boiling Sugar; and I do hereby declare that the following is a full, clear, and exact description of the same, reference being had to the accompanying drawings, forming part of this specification, in which—

Figure 1 is a longitudinal vertical section of a kettle-train with my improvement. Fig. 2 is a horizontal section of the same in a plane below the kettle-bottoms. Fig. 3 is a transverse vertical section of the same between the kettles.

Similar letters of reference indicate corresponding parts in the several figures.

My invention consists in the employment, for the purpose of supporting the kettles, of double arches supported partly by the side walls, and partly by pillars or piers between the kettles, by which means I am enabled to construct the canal or flue much wider than when single arches extending all across the canal or flue are used, as in the ordinarily-constructed kettle-train, and to obtain more room for the circulation of the flame and heated gaseous products of combustion at the sides of the kettles, and an increased heating effect on those parts.

To enable those skilled in the art to make and use my invention, I will proceed to describe it with reference to the drawings.

A A are the side walls of the flue, or, as it is generally termed, the "canal." B B are the double arches, and C C the piers or pillars for supporting the inner ends of the same, arranged centrally between the side walls and between the kettles D D, said piers being erected upon transverse walls E E, such as are commonly called "cascades." The side walls flare outward in an upward direction, as shown in Fig. 3, so as to give the upper part of the flue or canal a width at least as great as the upper and widest parts of the pans. F F are the fire-door entrances, which may be in one of the side walls, or in the end wall. The piers C C do not interfere with the draft, but leave the whole width of the flue open under the kettles.

What I claim as my invention, and desire to secure by Letters Patent, is—

A range of kettles on double arches, B B, supported partly upon the side walls, and partly upon center piers or pillars, C C, between the kettles, substantially as and for the purpose herein specified.

JOHN P. HENDERSON.
